(57) **CLAIM**

What is claimed is the ornamental design for a locking fishing plier, as shown and described.

DESCRIPTION

FIG. 1 is an upper front perspective view showing a locking fishing plier of Applicant's new design.

FIG. 2 is a lower rear perspective view of the locking fishing plier of FIG. 1.

FIG. 3 is an upper rear perspective view of the locking fishing plier of FIG. 1.

FIG. 4 is a right side elevation view of the locking fishing plier of FIG. 1, the left side elevation view an identical mirror image thereto.

FIG. 5 is a top plan view of the locking fishing plier of FIG. 1.

FIG. 6 is a bottom plan view of the locking fishing plier of FIG. 1.

FIG. 7 is a front elevation view of the locking fishing plier of FIG. 1; and,

FIG. 8 is a rear elevation view of the locking fishing plier of FIG. 1.

The dash-dash broken lines shown in the drawings illustrate portions of the locking fishing plier that form no part of the claimed design.
